DESIGN FOR A HAT

Sam Stricker, New York, N. Y.

Application September 21, 1938, Serial No. 80,023

Term of patent 3½ years

To all whom it may concern:

Be it known that I, Sam Stricker, a citizen of the United States of America, residing in New York city, in the Borough of Manhattan, county and State of New York, have invented a new, original, and ornamental Design for a Hat, of which the following is a specification, reference being had to the accompanying drawing, forming part thereof, wherein

Figure 1 is a front perspective view of a hat showing my new design.

Figure 2 is a rear view of the hat shown in Figure 1.

Figure 3 is a top plan view thereof.

The characteristic feature of my design resides in the combination on the specific hat disclosed of the specific band of stitching extending across the top of the tucked crown and returning to the same side in the manner shown in association with the linked ornament on the hatband as shown.

I claim:

The ornamental design for a hat, substantially as shown and described.

SAM STRICKER.
